LOAD HOISTING DEVICE

Cecil E. Pierce, West Southport, Maine

Application November 7, 1944, Serial No. 562,349

2 Claims. (Cl. 212—31)

1

The present invention relates generally to improvements in cranes and, as illustrated herein, consists more particularly in an improved load hoisting device particularly adapted for use on automotive trucks and the like.

Swinging cranes which are carried on a truck or wagon for hoisting a load from the ground and onto the body of the truck or wagon have not heretofore come into common use since the prior constructions have not been entirely satisfactory. The hoisting elements in many cases have been cumbersome and have taken up too much space on the body of the truck or wagon. It has also been difficult to provide controls for operating the crane or hoist which could be located within convenient reach of the operator. In many cases, also, the hoist or crane was so expensive that it proved to be more economical for the truck or wagon owner to load the vehicle by hand. Furthermore, in many hoisting devices the arc through which the crane arm could travel was limited and hence it was not always possible to place the end of the crane in the proper position to receive a load or to discharge a load.

One object of the present invention, accordingly, is to provide a simple, inexpensive crane or hoist by the use of which the above mentioned difficulties will be overcome. To this end and, as illustrated, the crane comprises a vertical member or mast to which is rigidly secured a horizontal arm which is constructed and arranged to form a cylinder for a pneumatic piston and which arm takes the weight of the load. The vertical member or mast is supported in a vertical standard fastened to the body of a truck and, as illustrated, the crane is readily removable from the standard.

With the above and other objects and features in view, the invention will now be described with particular reference to the accompanying drawings which illustrate one embodiment of the invention and in which:

Fig. 1 is a sectional view of a crane or hoist illustrating a preferred embodiment of the present invention;

Fig. 2 is a plan view of a portion of the swinging arm illustrating the relation between the movable sheave and the slot in the swing arm through which the support for the movable sheave projects;

Fig. 3 is a detailed sectional view illustrating the construction of the cylinder end of the horizontal swinging arm;

Fig. 4 is a plan view of the crane applied to an automotive truck; and

2

Fig. 5 is a view in rear elevation of the truck shown in Fig. 4.

The present invention is illustrated in Figs. 4 and 5 as applied to an automotive truck of usual construction having a platform 12 and a headboard 14 which is rigidly secured to the platform 12 by usual braces, not shown, so that it forms a rigid and substantial vertical wall to which the present hoisting device may be secured. The truck is provided with the usual racks 16 which form the sides of the truck body and are readily removable to permit loading of the truck.

The illustrated crane or hoist is rotatably mounted in a hollow tubular standard 20 having a flat plate 22 welded to its lower end. The plate 22 is provided with a plurality of holes for receiving the bolts 24 to secure the standard or base 20 firmly to the platform 12 closely adjacent the headboard 14. The upper end of the standard 20 is rigidly held in place by a U-bolt 26 extending through the headboard 14. In the present construction, which is designed particularly for loading potato barrels which weigh approximately 235 pounds, the standard 20 is formed of a 3½" pipe which has a wall approximately ¼" thick. This size of pipe has been found to be suitable for this particular purpose but it is evident that the size of the standard 20 and the thickness of the wall thereof may readily be varied depending upon the weight of the load to be handled.

The crane or hoist proper is provided with a vertical tubular member or mast 28 dimensioned to fit into the standard 20 in such a manner that it rotates freely therein. The upper end of the mast 28 is cut away or shaped to receive an elongated cylindrical member 30 which is welded near one end to the mast 28 and extends perpendicularly therefrom. The cylindrical member 30 may conveniently be formed of a 3" pipe having an outside diameter of 3½". The inside of the cylinder 30 is lined with a smooth bore liner 32 which fits snugly into the pipe to form a cylinder in which a piston 34 reciprocates. The inner end of the cylinder 30 projects beyond the mast or vertical member 28 and is threaded to receive an internally threaded cap 36. A gasket 38 is interposed between the inner end of the cylinder 30 and the cap 36. The liner 32, which may be a copper tube, terminates short of the outer end of the cylinder 30. A pipe or tube 40 having a 3" outside diameter is joined to the end of the cylinder 30 adjacent to the end of the liner 32. The tube 40 is welded to the cylinder 30, thus forming a rigid integral construction

which serves to maintain the liner 32 in position.

The tube 40 is provided with a slot 42 which is substantially equal in length to the length of travel of the piston 34. The piston 34 is provided with a piston rod 44 which is bolted at one end to the piston 34 in the usual manner and at its other end is provided with a sliding head 46 which fits into the inside of the tube 40. Adjacent the head 46 is provided a narrow support 48 rigidly secured to the outer end of the piston rod 44 by fastenings such as bolts or rivets 50 and extending outwardly through the slot 42 in the walls of the tube 40. The support 48 at its upper end carries a sheave 52 about which a cable 54 is rove. The cylinder 30 has secured thereto in alignment with the slot 42 in the tube or cylinder 40 a support 56 which is secured to the tube 30, preferably by welding. The support 56 extends substantially above a sheave 58 which is rotatably mounted on the support and forms an anchorage for one end of the cable 54. The cable 54 passes toward the free end of the horizontal arm comprising the cylinders 30 and 40 and about the aforesaid sheave 52 and returns toward the supported end of the horizontal arm and about the sheave 58 and then passes toward the free end of the horizontal arm provided with a sheave 60 which is supported on a pivot pin 62 passing through suitable openings in the tube 40. By means of the construction just above outlined, the piston 34 may be moved toward the right as viewed in Fig. 1 by compressed air supplied in a manner which will later be described, a distance of approximately two feet while the end of the cable 54 will be raised twice that distance or approximately four feet. The lower end of the cable 54 is provided with a grapple, not shown, which is designed to engage and grip, for instance, a barrel filled with potatoes.

The cylinder or tube 32 is provided with compressed air from any suitable source through a flexible tube 64 which is connected to a valve 66 having a control handle 68. The valve 66 is connected to a second valve 70 by a short tube 72. Thus when the valve 66 is opened compressed air is free to pass through the valve 66 and into the valve 70. The valve 70 is provided with a control handle 74 and with a vent 76 which discharges into the open air. The valve 70 is connected to the cylinder 32 by a tube 78 connected to a fitting having an opening therein leading into the interior of the tube 32.

When the valve 66 is opened by the operator to permit compressed air to flow through the valve 70 and the tube 78, the piston 34 and the movable sheave 52 will be forced to the right as viewed in Fig. 1, thus raising the lower end of the cable 54 as described above. When the cable has been raised the desired amount, the valve handle 68 is closed thus maintaining the cable 54 and its supported load in position and the horizontal arm comprising the cylinders 30 and 40 may be swung into any desired position over the platform 12 of the truck and the load may be deposited wherever desired within the radius of the horizontal load-carrying arm.

When it is desired to lower the end of the cable 54 and the grapple and load thereon, the handle 74 of the valve 70 is turned to such a position that the cylinder will vent through the opening 76 in the valve 70. The weight of the load on the cable will be sufficient to cause the piston 34 and the piston rod 44 and the parts carried thereby to move toward the left. When the load has been dropped the piston may be re-

turned to its original position with the piston bearing substantially against the end cap 36 by merely pulling downwardly on the cable.

From the above, it will be noted that the construction is simple and is formed with a minimum number of movable parts and that the controls or valves 66 and 70 are located in a position close to the cab of the truck in such a manner that they are at all times within easy reach of the operator. Furthermore, the horizontal arm comprising the cylinders 30 and 40 is sufficiently rigid to support and hoist the desired load and also to provide a cylinder in which the piston 34 and its associated parts may reciprocate.

In one aspect, accordingly, my invention comprises a hoisting device in which a tubular horizontal movable arm is utilized for the two functions of supporting and carrying the load, and also to supply a cylinder for fluid pressure operating means.

While the piston 34 has been described as moving a distance of approximately 2 feet in its cylinder and as raising the hoisting end of the cable 54 to a distance of approximately 4 feet, it will be understood that this specific description refers only to the particular embodiment of the invention shown herein for illustrative purposes and that it is well within the scope of the present invention to provide for a greater or lesser travel of the piston and a correspondingly greater or lesser movement of the hoisting cable. It is also contemplated that wherever a greater ratio of movement is required between movement of the piston and the hoisting cable, double sheaves may be utilized in place of the single sheaves shown in the drawings.

Having thus described my invention, what I claim as new and desire to secure by Letters Patent of the United States is:

1. A load hoisting device comprising a vertically disposed tubular mast, a horizontally disposed tubular arm rigidly secured adjacent one end to the upper end of said mast, means for rotatably supporting the mast and its arm, said arm containing a fluid pressure cylinder within its inner end and having a longitudinal slot extending outwardly beyond said cylinder and toward its outer free end, a piston slidable in said cylinder having a rod movable in said tubular arm and having a support extending outwardly through the slot therein, a sheave carried by said support and movable with the piston above said arm, stationarily mounted sheaves carried by the outer end and by the inner end portion respectively of said arm, a hoisting cable rove about the said last named sheaves and the sheave carried by the piston rod, and means for supplying a fluid pressure medium to said cylinder.

2. A load hoisting device comprising a vertically disposed tubular mast, a horizontally disposed tubular arm extending across the top of the mast and being closed at one end, said arm being rigidly secured adjacent to its closed end to the upper end of said mast, a base for rotatably supporting the mast and its arm, said arm containing a fluid pressure cylinder within its inner end and having a longitudinal slot extending outwardly beyond said cylinder and toward its outer free end, a piston slidable in said cylinder having a rod movable in said tubular arm and having a support extending outwardly through the slot therein, a sheave carried by said support and movable with the piston outside said arm, stationarily mounted sheaves carried by the outer

end and by the inner end portion respectively of said arm, a hoisting cable rove about said last named sheave and the sheave carried by the piston rod, and compressed air connections leading to the closed end of said tubular arm.

CECIL E. PIERCE.
